UNITED STATES PATENT OFFICE.

MAURICE ALLAND, OF ATLANTIC CITY, NEW JERSEY.

FOUNTAIN PEN.

Application filed June 10, 1925, Serial No. 36,104. Renewed July 2, 1926.

The object of the invention is to provide several improvements in writing instruments, and particularly in that class quite generally referred to as fountain-pens.

Another object is to provide a positive means for filling the reservoir of the fountain-pen with a liquid, which liquid though comprising water in the present instance may be the usual liquid ink or other types of fountain-pens to which this feature of the invention may be applied, said filling means making it possible with a most direct manual operation to expel a maximum quantity of the air from within the reservoir, and consequently upon being released insures the reservoir being filled to a maximum degree with but a single operation, and automatically resets the filling means.

A further object is to provide an improved feed which too can be used in many types of fountain-pens, but which is particularly adaptable for use in the one hereinafter described, said feed comprising an ingeniously designed channel through which air is permitted to flow with a maximum degree of freedom past the pen-point and into the reservoir, in order that an uninterrupted flow of water, or liquid ink, as the case may be, can flow steadily from the reservoir, past the inflowing air, and to the pen-point, as the operation of writing with the pen proceeds.

Still another object is to provide broadly for the manufacture of liquid ink in a fountain-pen adjacent to or in the immediate neighborhood of the pen-point, the reservoir of the pen in such case being supplied with water, while entirely outside of the reservoir and in fact close to the pen-point or nib there is positioned a soluble ink pellet, past and in contact with which the water from the reservoir flows and there makes the ink, which is discharged by and from the pen-point, said pellet being so mounted that when dissolved a renewing pellet may be most easily inserted in its stead.

Again, another object is to provide in such a pen a feed member, which when in normal writing position has a transversely extending aperture, a recess in the underside of said member spaced away from said aperture, and a dual holder normally containing ink-making pellets, one portion of said holder extending into and positioning a reserve pellet in said recess, and another portion of

said holder extending into and positioning an active pellet in said aperture and exposed to water as it flows from the reservoir past the feed member to the pen, the water upon contacting with said pellet dissolving the same gradually and causing fluid ink to be made in near proximity to the pen or nib.

And a still further object is to provide as a part of a fountain-pen a novel eraser for removing ink marks from writing paper or other usual types of writing material, said eraser comprising an abrasive "stone", which throughout the following specification and claims is intended to refer to those materials such as emery, carborundum, stone, pumice, and the like, which in suitable shapes are marketed as sharpening stones for metal tools than which they are much harder, and which materials are non-wearing as compared with paper and the like, such as is used for writing purposes.

With these and other objects in view, the present invention comprises additional novel details of construction and operation hereinafter fully brought out in the following description when read in conjunction with the accompanying drawings, in which Fig. 1 is a side elevation of a fountain-pen comprising one embodiment of the invention, and having one wall of its reservoir section broken away to show the interior thereof; Fig. 2 is a longitudinal section on the line 2-2 of Fig. 1; Fig. 3 is a transverse view on the line 3-3 of Fig. 2; Fig. 4 is a central vertical longitudinal section of the feed member hereinafter described; Fig. 5 is a transverse section of the same on the line 5-5 of Fig. 4; Fig. 6 is a bottom plan view of the soluble ink pellet containing member; Fig. 7 is a side elevation of the same; Fig. 8 is a side elevation of the "feed" member; and Fig. 9 is a plan view of the "feed" member.

Referring to the drawings, the body portion of the fountain-pen comprises an annular wall 1 surrounding a reservoir section 2, which is closed at one end 3, and at the other end 4 is externally threaded to receive the correspondingly threaded portion 5 of an angular cap 6, when the pen is not in use, the walls of said cap being provided with air passage-ways 7, and the interior of said cap terminating in one direction in the transversely extending wall 8, beyond which

is a magazine 9 adapted to hold a plurality of soluble ink pellets 10.

That portion of the walls of the cap 6 surrounding the outer portion of the magazine 9 is radially reduced at 11 and externally threaded to receive the correspondingly internally threaded portion 12 of a ferrule, which at its free end is provided with a relatively shallow annular flange 13 surrounding an axially positioned aperture, while against said flange and extending through said aperture is positioned a stone 14 formed of suitable material such as emery, carborundum, quarry stone, pumice, and the like, which is adaptable for erasing ink marks from the usual type of writing paper, and with respect to the paper and the usual types of yielding rubber erasers is substantially non-wearing and permanent.

20 The stone itself is provided with an inner flange portion 15, which is firmly secured in operative position between the flange 13 of the ferrule and the free reduced end portion 11 of the walls 6 of the cap.

25 That end of the reservoir portion opposite to the closure 3 has secured in it in any suitable manner a member 16 provided axially with a bore or throat 17, the inner end portion of the walls of said member being radially reduced at 18 and surrounded by the opened end portion 19 of a slender collapsible bag or pouch 20, said end portion being maintained in water and air-tight position by means of a suitable band 21.

30 The outer end portion 22 of the member 16 is formed in any suitable manner exteriorly and is provided with an enlarged axial bore 23 connected with the bore 17 by means of an annular plane shoulder 24 for a purpose hereinafter described.

35 Extending longitudinally along the outer surface of the bag 20 and upon one side thereof is a relatively inflexible plate 25, to the central portion of which is secured a lug 26, while the opposite end of said lug is provided with an axial bore, and internally threaded at 27 to receive the similarly but externally threaded reduced end portion 28 of an operating member 29, which extends 40 through an aperture 30 in the wall 1 of said reservoir section, and is provided with a sufficiently enlarged head 31 for engagement by the nails of one's thumb and first finger, the outer surface of said wall being notched at 32 so that the finger-nails may be readily positioned beneath the head 31, as will be evident by reference to Fig. 3.

45 The central portion of the opposite sides of the bag 20 are apertured at 33, and through said apertures extend a pair of interlocking rivets 34, themselves having a central aperture 35 through which the lug 26 is adapted to pass slidably when the head 31 is drawn outwardly manually, and upon being released is again drawn inwardly by

virtue of the resiliency of the walls of said bag.

50 Normally positioned within the enlarged bore 23 of the member 16 is a so-called feed-member illustrated in Figs. 2, 4, 5, 8 and 9. This feed member comprises a body portion 36, which is provided with a normally vertically extending saw-cut 37 in order to provide a passage through which air may pass vertically, as hereinafter described, in entering the throat 17 and bag 20, to relieve the vacuum and permit fluid to flow from said bag through the throat and to a penpoint or nib 38, the shank 39 of which pen-point embraces the upper side of the outer otherwise open side of a restricted channel extension 40 of the saw-cut 37, and at its innermost end said pen-point abutting against the shoulder 24 in the member 16.

55 The cutting of the feed member provides a bifurcated inner end portion, the opposite walls of which are relatively yielding. When the fountain-pen as an assembled unit is in its normal position for operating, and the feed member is in the position shown in Figs. 2 and 4, the lower free end portion of the channel 40 is gradually tapered at 41, so that there is but a restricted opening of the channel against the undersurface of the pen in the neighborhood of its point.

60 The inner wall of the channel 40 is also provided with a central saw-cut 42 in order to permit air to flow upwardly into said channel, and the under portion of said feed member is provided with an aperture 43, which extends upwardly to a channel 40 and through to the upper surface of the feed member, and is normally closed at its upper end by the pen-point itself. The feed member is also provided in its undersurface with a recess 44, co-axial with but spaced from the aperture 43, and not extending upwardly sufficiently far to connect with the channel 40.

65 Referring to Figs. 4, 6 and 7, there will be found a pair of cups having cylindrical sides 45, and closed at their inner ends by means of walls 46, said sides being provided with saw-cuts 47, which when a pellet 10 is dissolved below the upper extent of a cup in the aperture 43, the capillary attraction of the ink for the sides of the cut or slit, serves to impel the liquid through and out of said aperture 43, into the channel 41 and thence to the penpoint 38. The opposite end portions 48 of a connecting member 49 are secured in any suitable manner, as for instance by means of rivets 50, to the central portion of each of the walls 46, and these cups thus form a unit which when respectively filled with pellets 10 are insertable in the respective aperture 43 and recess 44, as shown in Fig. 4. When the pellet in the cup within the aperture 43 is dissolved, the pellet-containing unit may be readily removed so that

the other cup and its pellet, having been withdrawn from the recess 44, may be positioned in said aperture, the empty cup being then positioned within the recess.

5 In the operation of this device, the pellet-containing member is provided with the soluble ink-pellets for the magazine 9, and said pellets are operatively positioned as shown in Fig. 4 and with the feed member 10 in return in their respective operative positions shown in Fig. 2, the cap 6, however, being removed by unscrewing the threaded portion 5 from the threads 4, and thereafter placing the cap upon the opposite closed end 15 portion of the body portion of the device.

The head 31 is then manually withdrawn as far as possible until substantially the total length of the bag 20 is compressed against the upper portion of the wall 1 (as viewed 20 in Fig. 2), after which the lower portion 22 of the member 16 is immersed preferably in water or any other suitable solvent for the ink-pellets, the head 31 then being released and the resiliency of the walls of the bag 20 25 withdrawing the stud 26 and operating member 29 into their innermost positions as shown in Figs. 2 and 3, while in so doing the bag 20 has automatically filled itself with the solvent.

30 The pen is then withdrawn from beneath the surface of the solvent and is thereafter ready for use in the manner intended, namely, as a writing instrument, for as the pen-point 38 is brought into contact with writing material and is either manually or otherwise drawn across said material, the solvent by capillary attraction is drawn solely from the reservoir 20 through the throat 17, saw-cut 37, channel 40 and past 35 the soluble ink-pellet 10 in the aperture 43, and thence to the pen-point, where it is discharged upon the writing material in accordance with the manipulations of the pen in writing or otherwise.

40 In practise, it has been found that it requires approximately two fillings of the reservoir with the desired solvent, in order to dissolve completely the pellet that is operatively positioned in said aperture. When 45 this is done, however, the pellet-containing unit is reversed in position as hereinbefore described and a second pellet is brought into position from the recess 44 in the aperture 43, and the pen is again ready for use, and will continue to be as long as any of the solvent remains in the reservoir and its throat and a portion of the soluble ink pellets remains in the aperture 43. Obviously, when 50 both pellets have been dissolved, new pellets may be removed from the magazine 9 and placed in said holder for further use of the pen.

55 It is to be understood that the improved filling mechanism for the reservoir 20 in its broadest sense may be comprised within a

fountain-pen not provided with soluble ink-pellets but which depends upon liquid ink being drawn directly into the reservoir in distinction from the present instance in which only water enters the reservoir, and 70 the ink is manufactured in the immediate vicinity of the point of discharge from the pen-point and as the ink is used.

Furthermore, the feed member hereinbefore described has been so designed as to 75 permit a steady inward flow of and outward flow of fluid so as to provide a positive supply of ink for the pen and thus eliminating the usual interruptions due to fluid from the reservoir failing to flow by reason of the fact 80 that air is unable to pass inwardly through the feed member and into the reservoir. Still again, the magazine construction and improved eraser-stone above described is 85 adapted for use with many types of writing instruments and not alone with that herein described.

Having thus described my invention, what I claim and desire to protect by Letters Patent of the United States is:—

90 1. A fountain-pen, having a chamber provided with an opening, a collapsible bag connected at its open end to the walls of said chamber and communicating with said opening, a substantially rigid member lying 95 along and extending substantially the entire length of the outside surface of said bag, and means extending through a wall of the barrel of the pen and through said bag and connected with said member upon the opposite side of said bag, whereby substantially the entire length of said bag can be collapsed and the air expelled through said opening, and then substantially the entire bag full of 100 liquid sucked by and into the expanding bag 105 through said opening, by but a single operation.

2. A fountain-pen, having a chamber provided with an opening, a collapsible bag connected at its open end to the walls of said chamber and communicating with said opening, a substantially rigid member lying 110 along and extending substantially the entire length of the outside surface of said bag, a hollow rivet extending transversely through the walls of said bag, and means connected with said member through said hollow rivet and extending also through a wall of said chamber, whereby movement of said means in one direction collapses said bag to expel air and movement in the other direction permits said bag to expand and suck a liquid 115 thereinto through said opening.

3. A fountain-pen, having a chamber provided with an opening, a collapsible and automatically expandable bag connected at its open end to the walls of said chamber and communicating with said opening, a substantially rigid member lying along and 125 extending substantially the entire length of 130

the outside surface of said bag, a hollow rivet extending transversely through the walls of said bag, and means connected with said member through said hollow rivet and 5 extending also through a wall of said chamber, whereby pulling said means outwardly collapses said bag to expel air there-

from, and then releasing said means permits the resiliency of said expansible bag to suck a liquid thereinto through said opening and 10 return said means to its innermost position.

In testimony whereof I have affixed my signature.

MAURICE ALLAND.
